UNITED STATES PATENT OFFICE.

LE ROY BROWN, OF SAULT STE. MARIE, ONTARIO, CANADA.

HEAT-INTERCHANGING DEVICE.

1,367,944.

Specification of Letters Patent.

Patented Feb. 8, 1921.

Application filed September 21, 1918. Serial No. 255,126.

To all whom it may concern:

Be it known that I, LE ROY BROWN, of the city of Sault Ste. Marie, in the district of Algoma, in the Province of Ontario, Canada, have invented certain new and useful Improvements in Heat-Interchanging Devices, of which the following is the specification.

My invention relates to improvements in heat interchanging devices and the object of the invention is to devise simple rapid means for either cooling or heating various kinds of fluids whether in the form of a liquid or gas or in a semi-fluid state and it consists essentially of a series of parallel channels through which the fluid to be cooled passes, such channels being separated by intervening spaces through which the cooling medium flows as hereinafter more particularly explained.

Figure 1, is a longitudinal section through my device arranged for cooling or heating fluids passed therethrough under pressure or vacuum.

Fig. 2, is a sectional view on line $x-y$ Fig. 1.

Fig. 3, is a sectional view on line $x'-y'$ Fig. 1.

Fig. 4, is a perspective detail of one of my unit members.

Fig. 5, is a longitudinal sectional view through my cooling device arranged for cooling oil with water where both are at atmospheric pressure.

In the drawings like characters of reference indicate corresponding parts in the various figures.

I will first refer to Figs. 1 to 4 inclusive.

1 indicates a casing comprising a lower casing member 1^x , an intermediate casing member $1'$ and an upper casing member 1^z . The lower member 1^x is provided with an inlet 1^s and an outlet 1^t . The upper casing member is provided with an inlet 1^s and an outlet 1^t . The intermediate casing member is provided with an inlet 1^s and an outlet 1^t . The liquid to be cooled is fed through the inlets 1^s and 1^t and passed out from the outlets 1^t and 1^s . The cooling medium passes into the device through the

inlet 1^s and passes out through the outlet 1^t .

In order to separate the liquid to be heated or cooled from the fluid forming the temperature changing medium I have provided the following device.

Within the upper and lower casing members 1^x and 1^z is located the member illustrated in Fig. 4. This member comprises a rectangular plate member 2 provided with a series of parallel slots 3 from which depend hollow flanges 4 extending parallel one to the other, the side walls of which may be either vertical or slightly inclined so as to taper toward the outer end of the flange as shown in Fig. 4. The flange-like portion 2^x formed by the edge of the plate 2 extending beyond the depending flanges 4 rests, when inserted in the lower unit 1^x , upon the top edge of such unit so that the flanges depend into the casing member. When in this position it will be seen that a plurality of parallel channels are formed extending longitudinally of the casing member 1^x between each of the depending flanges 4 and through which the fluid to be cooled passes as it travels from the inlet 1^s to the outlet 1^t . Upon the flange 2^x resting upon the upper edge of the casing member 1^x rests an out-turned flange 1^y of the central member $1'$. The flange of the lower casing member 1^x and flange 2^x and flange 1^y are suitably secured together. The upper edge of the central casing member $1'$ is provided with an out-turned flange 1^{10} . Upon the out-turned flange 1^{10} rests the out-turned flange 2^x of the upper member 2 and upon the flange 2^x of the upper member 2 rests the out-turned flange of the upper casing member 1^z . These flanges are also suitably connected together. By this means parallel channels are also formed in the upper casing member 1^z through which the fluid to be cooled passes as it travels from the inlet 1^s to the outlet 1^t . The cooling medium which passes through the inlet 1^s enters the central portion of the device formed by the member $1'$ and passes into the interior of the hollow flanges 4.

It will thus be seen that the fluid to be cooled passes against the outside face of

the walls of the hollow flanges 4 and the cooling fluid passes against the inside face of the walls of the hollow flanges 4 thereby providing for heat transfer, the fluid passing into the interior of the flanges if of lower temperature than the fluid to be cooled serves to lower the temperature of such fluid, the heat transfer being effected through the walls of the flanges 4. Similarly if it is designed to raise the temperature of the fluid passed to the upper and lower casing members 1^x and 1^z the fluid passed into the central casing member is of relatively higher temperature and serves 15 to raise the temperature of the fluid passing against the outside face of the walls of the flanges.

In order to insure that the fluid fed into the central casing member is utilized to the 20 greatest extent such inner member is provided with baffle plates 5, 6 and 7, the baffle plate being provided with tongues 5^x and 6^x extending up into the hollow flanges of the upper cooling unit 2, the baffle plate 6 also being provided with short tongues 6^y which pass into the hollow flanges of the lower cooling unit 2. The baffle plate 7 is provided with tongues of a similar nature which extend respectively into the hollow flanges 4 of 25 the upper and lower units 2. Cross plates 9 are also provided extending between the baffle plate 5 and the end wall of the middle unit casing 1^z.

By this means the cooling or heating fluid 30 which is fed through the inlet 1^x is distributed by the baffle 7. Part is directed into the upper hollow flanges 4 and part into the lower hollow flanges 4. The remainder passes through slots opposite the inlet. Part 40 of the fluid passes beneath the baffle plate 6, and part above. Convection currents will cause the warmer portion of the cooling medium to rise and the baffle 5 is arranged so that only the upper and warmer portion 45 of the cooling medium will find its way through the outlet 1^z.

In order to distribute the oil or other fluid to be cooled so that it passes evenly through the parallel channels formed by the flanges 50 4 I have provided perforated plates 10 which extend against the ends of the flanges at the inlet end of the temperature interchange unit. At the opposite ends of the flanges I have provided plates 11 which allow the 55 fluid which has either been heated or cooled to the greatest extent to pass off through the outlets 1^y and 1^z. Whenever a fluid that contains a gas in solution or that gives off vapor, is passed through the interior of the 60 hollow flanges, a gas release will be necessary at the top of each hollow flange.

In Fig. 5 I have illustrated my device adapted for cooling fluids which are fed under atmospheric pressure. In the device 65 as arranged in Fig. 5 I only employ the

lower casing member modified as illustrated in Fig. 1 and the flanged member 1' and member 2 modified, the upper member 1^z being dispensed with. In the hollow flanged member 2 shown in Fig. 5 the flange like 70 portion 2^x is dispensed with and the sides are carried vertically upward to form an open top box, in the ends of which the inlet and outlet are placed.

13 indicates the inlet through which 75 water is passed to the interior of the unit. 12 indicates the outlet through which water is discharged. In this figure the outer casing 14 is preferably longer than the member 2 and is provided at the inlet end with 80 a perforated wall 14^x forming a compartment 14' into which oil is fed from a valve 15 which is controlled by a float 16. The oil is fed into the compartment 14, passes through the perforated wall 14^x and flows 85 longitudinally between the flanges of the member 2. At the opposite end of the casing is a cross wall 14^z forming a weir. Between this weir and the end of the unit 2 is a wall 14^y. This wall baffles the warmer 90 fluid which by convection finds its way upward and allows the cooler fluid from the bottom to rise and overflow, the weir passing out through the discharge orifice 17.

From this description it will be seen that 95 I have devised a very simple device whereby a heat interchange may be effected between various fluids, such heat interchange being accomplished rapidly and efficiently.

Also it will be seen that I have devised a 100 simple means whereby both exterior and interior walls of the unit may be quickly exposed for cleaning purposes.

In certain cases where the fluid is of such a consistency that it has a tendency to cling 105 to the walls of the flanges it may be necessary to employ scrapers. I do not illustrate or describe these in detail as they may be of any suitable construction commonly used in other devices.

What I claim as my invention is:

1. A heat interchanging device comprising 115 a casing having an inlet at one end and an outlet at the opposite end, a member supported upon the upper edge of the open top of the casing and provided with a series of parallel depending hollow flanges extending longitudinally of the casing and between which the fluid passes from the inlet to the outlet of the casing, a perforated plate extending over the ends of the flanges at the inlet end, and means for feeding a temperature interchange fluid into and through the hollow flanges.

2. A heat interchanging device comprising 120 a casing having an inlet at one end and an outlet at the opposite end, a member supported upon the upper edge of the open top of the casing and provided with a series of parallel depending hollow flanges extend- 130

ing longitudinally of the casing and between which the fluid passes from the inlet to the outlet of the casing, means for feeding a temperature interchange fluid into and through the hollow flanges, and means for

5 directing the flow of the heat interchange fluid medium into the interior of the hol-

low flanges as it passes therethrough from the inlet to the outlet end.
